EDGE SETTING MACHINE

Edwin W. Smith, Beverly, Mass., assignor to
United Shoe Machinery Corporation, Flemington, N. J., a corporation of New Jersey

Original application May 17, 1940, Serial No. 335,756. Divided and this application July 1, 1941, Serial No. 400,608

5 Claims. (Cl. 12—78)

This invention relates to burnishing machines and is illustrated herein as embodied in tool supporting mechanism adapted for use in an edge setting machine of the type disclosed in United States Letters Patent No. 2,283,239, granted May 19, 1942, upon an application which was filed in the names of Laurence E. Topham and Edwin W. Smith and of which the present application is a division.

In machines of the type above referred to, the high operating speeds of tool holders cause considerable wear on the burnishing tools due to the play permitted between the tools and their carriers by the latching devices now in general use for holding tools on the carriers. The travel of the high-speed tools is very small and the tools, and in many cases the carriers, wear to such an extent that a large proportion of the movement of the tools is lost and, accordingly, the tools, and less frequently the carriers, must be discarded.

It is an object of the present invention to provide improved means for so latching the tools and the tool carriers as to eliminate play between these members when they are oscillated at high speeds and thereby to increase the life of the tools or the carriers or both. To this end, each tool carrier is provided with a shoulder which is adapted to be engaged by one side of the tool, and a member which is adapted to engage the other side of the tool and to clamp it against the shoulder.

The various features of the invention will be understood and appreciated from the following detailed description read in conjunction with the accompanying drawing, in which

Fig. 1 is an angular view, partly broken away, of the operating head of the illustrative machine; and

Fig. 2 is a vertical longitudinal section, partly broken away, of the head of the machine.

In the illustrative construction there is shown a shaft 29 (Fig. 1) which is rotatably mounted in a bearing 22 and is oscillated or vibrated back and forth at a high rate of speed by driving mechanism of the type illustrated in United States Letters Patent No. 2,190,810, granted February 20, 1940, on an application filed in the name of L. E. Topham. Slidably and rotatably mounted in the shaft 29 is a spindle 24 which projects rearwardly from a holder 26, the holder being urged in a direction indicated by reference numeral 28 lengthwise of the axis 30 of the shaft by a spring 32 which is mounted in a cylindrical opening in the spindle.

The oscillating shaft 29 is provided with a com-

paratively large head 34 having a pair of oppositely disposed notches 36 (Fig. 1) which form part of the driving connection that causes the holder 26 to move in unison with the oscillating shaft 29. The remainder of the driving connection is formed by a pair of lugs 38 of the holder which are held in the notches 36 by the action of the spring 32. Attached to and forming part of the head 34 are a pair of oppositely inclined arcuate plates 40 which extend obliquely to the direction of oscillation of the shaft 29, the plates being so located that their ends form the side walls of the notches 36. The plates 40 are attached to the head 34 by screws 42 and form runways down which the lugs 38 ride when the tools are shifted 180° about the axis 30 upon thrusting a hand lever 44 rearwardly through mechanism which is described in said Letters Patent No. 2,283,239.

10 The holder 26 has a pair of bosses 46 each having a cylindrical opening or hole 48 shaped and arranged to receive a spindle 50 of a tool carrier 52. The carrier spindles 50 are slidably and rotatably mounted in the cylindrical openings 48 and have flat surfaces 54 formed in their inner ends and enlarged heads 56 formed in their outer tool-engaging ends.

15 As above explained, latches (not shown) now in general use for holding tools on the tool carriers are of a yielding character which permits considerable play between these members when they are oscillated at high speeds used in machines of the type disclosed in the above-mentioned Topham patent, with the result that considerable wear develops between the tool carriers and the tools. Since the operating movement of the tool is very small, being in the vicinity of $\frac{1}{16}$ of an inch, eventually the wear between the tool and the tool carrier reduces the movement of the tool to a negligible amount, rendering the tool useless so that it must be discarded. This difficulty is overcome by the tool clamping device illustrated herein which holds a tool 58 firmly in the tool carrier 52 and prevents relative movement between these members when they are oscillated at a high speed.

20 The tool 58 has an end face 100 (Fig. 1) designed for engagement with the work, and a pair of side faces 102 and 104 (only the left edge of the face 102 being visible in the drawing) which intersect the path of vibratory movement of the tool. In the construction illustrated herein the faces 102 and 104 not only intersect the path of movement of the tool, but are normal to said path.

The clamping device consists of a shoulder 60 which extends from one side of the enlarged tool carrier head 53 where it is adapted to engage a relatively large area of the side 102 of the burnishing tool 53. A relatively large area of the opposite side 104 of the tool 53 is engaged by the roughened side of a plate 62 which is fastened on the tool carrier head by a screw 64. The inner face of the plate 62, which is adjacent to the tool carrier head 53, is recessed from a point a slight distance beyond the head adjacent to the tool to a rib 66 on the end of the plate. When the screw 64 is tightened, the plate will fulcrum about the rib 66, causing the roughened part of the plate 62 to press the tool 53 against the shoulder 60, thereby clamping the tool between them so that there can be no relative movement between the tool and the tool carrier when these members are oscillated. The arrangement of the clamping faces of the tool in intersecting relation to its vibratory path of movement tends to offset any danger of the tool being loosened in its clamp by reason of the sudden and frequent reversal of movement.

The tool carrier spindles 50 are permitted a limited amount of rotative and axial movement in the holes or openings 48, which movement allows them to follow changes in the curvature according to the sole edge. Inward movement of the spindles 50 resulting from the pressure of the work is resisted by balls 68 carried by the inner ends of springs 70, the balls being located beyond the inner ends of the tool carrier spindles 50 and being urged in an outward direction by the springs. Rotation of the tool carrier spindles 50 is resisted by the lower ends of a pair of depending arms 72 which extend from a light plate 74 of spring material and engage the flat surfaces 54 formed on the spindles. The plate 74 extends transversely to the arms 72 and is provided at its opposite ends with openings which fit around the ends of posts 76, which also serve as mounting means for the springs. By using the light plate 74 of spring material and locating it centrally of the head of the tool holder 26, the relatively heavy eccentric spring-pressed latches, which have heretofore been used yieldingly to resist rotation of the tool carriers and spindles, have been eliminated, thereby reducing the inertia of the tool holder and the vibrations caused by the frequent reversals in the direction of its motion.

The above-described plate 74, which resists rotation and limits the outward movement of the tool carrier spindles 50, is not claimed herein, but is disclosed and claimed in a divisional application, Serial No. 473,053, filed January 21, 1943, in my name.

Having described my invention, what I claim as new and desire to secure by Letters Patent of the United States is:

1. In a burnishing machine, a vibratory holder, a carrier having a portion which registers with and through which the carrier is supported in

the holder, a burnishing tool having an end face designed for engagement with the work and having also a pair of oppositely disposed side faces, said carrier having a shoulder which is rigid with relation to said registering portion of the carrier and is adapted to be engaged by one of said side faces of the burnishing tool, a plate adapted to engage the opposite side face of the burnishing tool, and means for forcing the plate toward the shoulder on the tool carrier in order to clamp the tool to the carrier and thereby prevent relative movement between the tool and the carrier when they are vibrated with the tool holder.

2. In a burnishing machine, a vibratory tool holder, a carrier mounted on said holder, a burnishing tool, said carrier comprising a fixed jaw arranged to be engaged by one side of the burnishing tool, a movable jaw fulcrumed on the carrier and arranged for engagement with the opposite side of the tool, and means for forcing the movable jaw toward the fixed jaw to clamp the burnishing tool against the fixed jaw.

3. In a burnishing machine, a vibratory tool holder, a carrier mounted on said holder, a burnishing tool, said carrier comprising a head having an offset jaw arranged for engagement with one side of the burnishing tool, a movable member having a jaw arranged for engagement with the opposite side of the burnishing tool and a rib arranged for pivotal engagement with the head, and means for forcing the jaw of the movable member toward the jaw on the head to clamp the burnishing tool against the fixed jaw.

4. In a burnishing machine, a vibratory holder, a carrier mounted on said holder, a burnishing tool having an end face designed for engagement with the work and having also a pair of side faces which intersect the path of vibratory movement of the tool, said carrier comprising a fixed jaw arranged to be engaged by one of said side faces of the burnishing tool, a movable jaw fulcrumed on the carrier and arranged for engagement with the opposite of said side faces of said tool, and means for forcing the movable jaw toward the fixed jaw to clamp the burnishing tool.

5. In a burnishing machine, a vibratory holder, a tool carrier, a burnishing tool having an end face designed for engagement with the work and having a pair of oppositely disposed side faces, said carrier having a fixed jaw engaged by one of said side faces of the tool, a movable jaw fulcrumed on the carrier and arranged for engagement with the other side face of the tool, means for forcing the movable jaw toward the fixed jaw to clamp the burnishing tool against the fixed jaw, the tool carrier being mounted in the holder with provision for sliding of the carrier as the work is pressed against the tool, and means for limiting said sliding movement of the carrier.

EDWIN W. SMITH.
